UNITED STATES PATENT OFFICE.

ELOY NORIEGA, OF MEXICO, MEXICO.

TELEPHONE-TRANSMITTER.

SPECIFICATION forming part of Letters Patent No. 508,829, dated November 14, 1893.

Application filed February 4, 1891. Serial No. 380,172. (No model.)

To all whom it may concern:

Be it known that I, ELOY NORIEGA, of Mexico city, Mexico, have invented a new and Improved Microphonic Telephone-Transmitter, of which the following is a specification, reference being had to the annexed drawings, forming a part thereof, in which—

Figure 1 is a side elevation, partly in section, of my improved microphonic telephone transmitter. Fig. 2 is a vertical transverse section of the same. Fig. 3 is a rear elevation of a modified form. Fig. 4 is a vertical transverse section; and Fig. 5 is a front elevation of a complete telephone, including the receiving and transmitting instruments, induction coil and signaling mechanism, also showing a modified form of the transmitter.

Similar letters of reference indicate corresponding parts in all the views.

20 The object of my invention is to provide a microphonic telephone transmitter, capable of utilizing a heavy current, and of producing the variations of current necessary for the transmission of speech over long distances; also to provide a transmitter which will remain in adjustment and work uniformly under all conditions.

My invention consists in the combination with a diaphragm provided with an electrical 30 conducting surface, a series of carbon bars attached to the diaphragm and bearing upon the conducting surface, and an adjustable bar provided with a chamber containing elastic absorbent material held against the carbon bars, all as will be hereinafter more fully described.

The annular frame A, is provided at the top and bottom with arms B, B', and with apertures a for receiving the screws by which 40 the frame is fastened to the telephone box. Upon diametrically opposite sides of the annular frame are secured spring clips b, which extend inwardly over the diaphragm C, and hold it in place in the frame A. The edge 45 of the diaphragm is inclosed in a soft rubber band c, which modifies the vibrations of the diaphragm and prevents any electrical connection between the diaphragm and the frame A.

50 Upon the rear face of the diaphragm C is secured a thin plate of conducting material,

and to the diaphragm are bolted two carbon bars D, D', in which are made transverse holes for receiving the ends of the carbon rods d, which fit the holes loosely and rest normally upon the thin plate of conducting material attached to the diaphragm. The carbon bar D is provided with a conductor e, and the carbon bar D', in a similar way, is provided with a conductor e'.

To the arm B, is attached a spring f, which extends toward the arm B', and parallel with the diaphragm C. To the spring f is secured a bar E, which is provided at its upper end with a lug g, and is angled at its lower end to adapt it for engagement with the adjusting screw F. To the lug g is attached a spring h, which extends downwardly parallel with the diaphragm C, and carries a chambered bar G, in which is placed a body i, of fibrous, absorbent material which rests upon the carbon rods d, and presses them lightly against the thin carbon plate d', attached to the diaphragm. The pressure of the absorbent material i upon the carbon rods is regulated by turning the screw F, in one direction or the other, which by engaging the angled end of the bar E, causes it to move inwardly or outwardly as required.

The frame A is secured to the telephone 80 box cover l, which is provided with a mouth-piece I, located opposite the center of the diaphragm C. The diaphragm C is preferably made of wood, spruce having been found by experiment to be the best wood for the purpose. The diaphragm is protected against the effects of moisture of the breath or the atmosphere, by a coating of water-proof varnish, such as shellac.

In the modifications shown in Figs. 3 and 90 4, the diaphragm C is clamped in a cell A', by the mouth-piece I', which screws upon the cell. To the diaphragm C are attached the carbon bars D, D', as in the other case, and the carbon rods d, which are like those already described, are pressed against the diaphragm by fibrous absorbent material preferably absorbent cotton contained in a case G', carried by a spring h' secured to the wall of the cell A', and the adjustment of the 95 spring h' is effected by the screw F' passing through the back of the cell A'. The cell A'

may be made of metal or insulating material such as hard rubber, but in any case the back *j* of the cell must be made of insulating material. The binding posts *e*², *e*³, attached to 5 the back *j*, are connected electrically by flexible wires with the bars *D*, *D'*. The back of the cell *A'*, in this case is threaded externally to permit of screwing it into the door of the casing of the telephonic apparatus.

10 In the form of transmitter shown in Fig. 5, the construction is the same as that shown in Figs. 1 and 2, with the exception of the omission of the bar *E*, the spring *h*, and the body *i* of absorbent material, and the ends 15 of the rods *d*, which are made conical and inserted in conical cavities in the carbon bars *D*, *D'*. The casing *J*, which contains all the working parts of the telephone, with the exception of the receiver, consists of a body *k* 20 and a cover *l*, the two parts being connected by the hinges *m*, *m'*, *m*², *m*³. To the inside of the cover *l* is secured the annular frame *A*, and in the cover is placed the induction coil *K*.

In the body of the box is arranged a mag- 25 neto-electric machine *L* of the usual description, also a magneto call bell *M*, of the kind commonly used in connection with telephones, and in one side of the box case is pivoted a switch lever *N*, which extends outwardly 30 through the side of the box, and is bent upward to form a key for receiving the telephone receiver *O*. The inner end of the lever *N* is connected with one end of a spiral spring *n*, the other end of which is attached to a stud *o*, and in the path of the inner end of the lever *N*, is arranged a contact point *p*, which is touched by the lever *N*, when the said lever is moved by the spring *n* after lifting the telephone receiver *O* from the outer end of the 35 said lever. The body *k* of the box is furnished with binding posts *q*, *q'*, and the cover *l* is furnished at the bottom with binding posts *r*, *r'*, and at the top with binding posts *s*, *s'*.

The poles of the battery *P* are connected 40 with the binding posts *r*, *r'*. The binding post *r* is connected with one terminal of the primary wire of the coil *K*, the other terminal of the said primary wire being connected with the hinge *m*², which is connected electrically with the stud *o*. The binding post 45 *r'* is connected with the wire *e'* leading to the carbon bar *D'*, and the wire *e* attached to the carbon bar *D*, is connected with the hinge *m'*, and the hinge is connected electrically with the contact point *p*, so that when the telephone receiver *O* is lifted from the lever *N*, the said lever is tilted by the spring *n*, so as to touch the contact point *p*, thus 50 closing the local circuit.

55 60 The line circuit is from the ground *Q* through the binding post *q'*, hinge *m*³, the secondary wire of the induction coil, binding post *s'*, one branch of the double cord *R*, to and through the telephone receiver *O*, back 65 to the binding post *s*, thence through the hinge *m* to the binding post *q*, and through the line *S* to the distant station.

The signaling circuit is from the ground *Q* through the binding post *q'*, the polarized bell *M*, the magneto *L*, the armature of the magneto to the stud *o*, through the spring *n*, lever *N*, contact point *p'*, to the wire extending to the binding post *q*, thence over the line to the distant station.

When sounds are uttered in the mouth 75 piece of the transmitter, the diaphragm is vibrated and the current in the primary circuit is varied by the variable contact of the carbon rods *d* with the carbon lining of the diaphragm and with the bars *D*, *D'*, and electrical impulses are generated in the secondary wire of the coil, which are transmitted to the distant station, and act upon the telephone receiver to produce sounds like those made in the mouth piece of the transmitter. 80 85

Although the thin coating of carbon attached to the diaphragm short circuits the electrodes to some extent, still when the electrodes are vibrated by the movements of the diaphragm, the contact of the electrodes with the thin coating of carbon varies the resistance of this part of the circuit, and thus adds materially to the efficiency of the instrument. 90

The carbons used in my microphone are made according to one of the following formulas: 95

Formula No. 1.—Carbon (charcoal), forty-six per cent.; carbon (coke), forty-four per cent.; water saturated with boric acid at fifty per cent., ten per cent. 100

Formula No. 2.—Carcon (soft charcoal), forty-six per cent.; carbon (coke), thirty-three per cent.; water saturated with boric acid at forty-six per cent., eight per cent.; plumbago, thirteen per cent. 105

Formula No. 3.—Carbon, sixty-three per cent.; graphite, twenty-two per cent.; plumbago, seven per cent.; water saturated with boric acid at fifty per cent., seven per cent.; tar, one per cent. 110

Formula No. 4.—Carbon (charcoal), fifty per cent.; carbon (coke), four per cent.; graphite, thirty-two per cent.; plumbago, six per cent.; tar, one per cent.; water, five per cent. 115

Formula No. 5.—Graphite, sixty-six per cent.; carbon, twenty-five per cent.; tar, one per cent.; water, eight per cent. 120

Formula No. 6.—Carbon, sixty-six percent.; graphite, thirty per cent.; water saturated with boric acid at fifty per cent., four per cent. 125

Formula No. 7.—Carbon, seventy-four per cent.; graphite, nineteen percent.; water saturated with gum-lac and alcohol at fifty per cent. 130

I do not limit myself to the formulae enumerated, nor to the quantities stated, for these can be varied as desired. Carbons made according to my method are suitable for all classes of microphones. 135

The carbons are prepared according to the formulae as follows: Pulverize it until reduced to a very fine powder, and then pass it through a fine sieve of silk or metal, so as to

eliminate any lumps which would be prejudicial in making the paste. The paste, which is produced by mixing the carbon with the other substances and the water, is submitted to a pressure which can be varied from seventy-eight to ninety atmospheres. The strips, bars or cylindrical carbons (for any form can be obtained) which are thus obtained, and which can be of the desired size, are placed immediately in an oven of the proper form and heated to a red heat, more or less, 350° to 380° centigrade. At this temperature all non-conducting substances are destroyed, the conductivity of the others being greatly increased when the vulcanization takes place. By this operation, carbons are obtained which are very hard, dense and homogeneous, not easily broken, and according to the experiments made, are shown to be superior conductors for the transmission of vocal and other sounds.

The plate of carbon at the back of the diaphragm slightly decreases the resistance of the circuit, but the principal object of this construction is to be able to divide or subdivide the current between the plates and the bars of carbon, if desired. By this means three improvements in the system of carbon microphones are obtained. These are as follows: First, when the resistance of the microphone is excessive, the telephone messages are confused, so that articulate sounds are scarcely perceptible; this difficulty is increased with an increase of the distance over which conversation is carried on. With the carbon plate introduced into the combination, a perfectly clear and distinct transmission is obtained over a largely increased distance. Second, as the pressure of the carbon plate on the diaphragm can be increased more or less and the pressure of the cylinders against the plate can be varied, and the pressure of the absorbent material on the cylinders can

be varied, a more uniform action may be secured, the resistance being divided or subdivided as above stated, throughout the various contacts and bodies of carbon, thus causing a part of the current to pass through the plate, and a part through the carbon bars. Third, the absorbent porous material is inserted for the purpose of collecting all the moisture of the carbon electrodes. It is well known that carbon is quite hygroscopic, and consequently carbon electrodes absorb water easily and with very slight changes of temperature. Water is prejudicial to the transmission of speech and to a clear delivery. The absorbent material removes the water from the carbon and greatly improves the action of the microphone.

Having thus described my invention, I claim as new and desire to secure by Letters Patent—

1. In a microphonic telephone transmitter, the combination, with a diaphragm of non-conducting material, of a thin conducting lining attached to the diaphragm, apertured carbon bars secured to the diaphragm, transverse carbon rods having their ends inserted in the apertured bars with their sides resting upon the metal lining of the diaphragm, and means for pressing the transverse carbon rods forward against the conducting lining of the diaphragm, substantially as specified.

2. A carbon electrode for microphones, formed of charcoal, coke, and a solution of boric acid, combined in about the proportions stated.

3. A carbon electrode for microphones, formed of charcoal, coke, graphite, and an aqueous solution of boric acid, combined in about the proportions stated.
